SUPERHETERODYNE RECEIVER

Walter van B. Roberts, Princeton, N. J., assignor
to Radio Corporation of America, a corpora-
tion of Delaware

Application February 15, 1933, Serial No. 656,793

8 Claims. (Cl. 250—20)

My present invention relates to superhetero-
dyne receivers, and more particularly to a novel
method of, and means for, simultaneously ad-
justing both the super-audible amplification of
the receiver and local oscillator intensity.

It may be stated that it is one of the main
objects of the present invention to provide a
heterodyne receiver wherein there can be simul-
taneously varied the amplification of radio fre-
10 quency signal energy and heterodyne strength,
this simultaneous variation particularly func-
tioning as a volume control variation for the
receiver.

Another important object of the present in-
15 vention is to provide, in a superheterodyne type
of radio broadcast receiver, a unitary means for
simultaneously varying the gain of the radio
frequency amplifier, the gain of the intermediate
frequency amplifier, and the intensity of the
20 output of the local oscillator.

Another object of the present invention is to
provide a superheterodyne receiver which in-
cludes a means for substantially reducing the lo-
cal oscillator strength when receiving local sta-
25 tions, thereby lessening radiation interference.

Still another object of the present invention is
to provide a manual volume control device for a
superheterodyne radio receiver, the device com-
30 prising a means for simultaneously varying the
gain of the radio frequency amplifier and local
oscillation strength without in any way affecting
the tuning of the local oscillator.

Still other objects of the present invention are
to improve generally manual volume control de-
35 vices for superheterodyne receivers, and particu-
larly to provide for this type of receiver a
volume control device which possesses consider-
able operating advantages when receiving local
40 stations, is reliable in operation, and is economi-
cally manufactured and assembled.

The novel features which I believe to be char-
acteristic of my invention are set forth in particu-
larity in the appended claims; the invention
itself, however, as to both its organization and
45 method of operation will best be understood by
reference to the following description taken in
connection with the drawing in which I have
indicated diagrammatically an arrangement
whereby my invention may be carried into effect.

50 Referring now to the accompanying drawing
wherein there is shown in diagrammatic man-
ner a superheterodyne receiver, adapted to re-
ceive broadcast signals from 500 to 1500 kilo-
cycles, it is to be noted that only so much of the
55 circuit details of the receiver is shown as is

necessary to a proper understanding of the con-
struction and functioning of the present inven-
tion. The receiver, as is well known to those
skilled in the art, comprises a grounded an-
tenna circuit A which is coupled, as at M₁, to 5
the tunable input circuit of a radio frequency
amplifier tube 1 of the screen grid type. The
input circuit of the tube includes the variable
tuning condenser 2, having its rotor elements
grounded.

10 The screen grid and plate electrodes of tube 1
are adapted to be connected to appropriate
sources of positive potential, and the plate cir-
cuit of tube 1 is coupled, as at M₂, to the tunable
input circuit of the first detector stage. The 15
power supply source is not shown, but the re-
sistor R₁ from which the various positive poten-
tials are derived is shown connected across this
source. Of course, those skilled in the art are
well acquainted with the fact that such a source 20
may be the output of the usual rectified alter-
nating current filter circuit, or the output of a
direct current supply system.

25 The high voltage end of the divider R₁ is
designated by the usual plus sign, while the low
voltage side is designated by the customary minus
sign. Across the divider R₁ is connected a pair
of resistors R and R₂. The resistor R is a va-
30 riable one, while the resistor R₂ is fixed. The
negative side of the resistor R₂ is grounded.

35 The screen grid and plate circuits of tube 1,
as well as the various other tubes, may be con-
nected to the appropriate positive points along
the divider R₁. However, only such electrode
connections will be described as are necessary to 35
a proper understanding of this invention. The
cathode of tube 1 is connected, as by a lead 3,
to the point 4 on the fixed resistor R₂, and the
lead 3 includes the normal bias resistor r₁. A
40 radio frequency by-pass condenser C₃ is con-
nected between the cathode of tube 1 and the
grounded side of the variable condenser 2.

45 The first detector circuit includes in its out-
put a circuit resonant to the operating inter-
mediate frequency, and this circuit is coupled, 45
as at M₃, to the resonant input circuit of the
intermediate frequency amplifier tube 5, of the
screen grid type. The plate circuit of the tube
5, as well as the grid circuit of the tube, is fix-
edly tuned to the operating intermediate fre- 50
quency. The output of the second detector is
impressed upon the usual audio frequency am-
plifier, and the amplified audio signals are then
reproduced in any customary manner.

55 The screen grid and plate circuits of tube 5 are

connected to appropriate points of positive potential on the divider R_1 . The cathode of tube 5 is connected, through a lead 6, to a point 7 on the fixed resistor R_2 which is more negative than the point 4. The lead 6 includes a bias resistor r_2 , and the high potential side of the bias resistor r_2 is connected through the radio frequency bypass condenser C to the grounded side of the resonant input circuit of tube 5.

10 The local oscillator circuit of the receiver includes the screen grid tube 8 having its cathode connected to point 9 on the resistor R_2 , which point is positive with respect to points 4 and 7, and this connection is made through a lead 10 which includes the resistance 11. The input circuit of the local oscillator tube 8 comprises an inductance coil 12 shunted by a variable tuning condenser 13, the rotor elements of the condenser 13 being grounded. The high potential side of the circuit 12, 13 is connected to the grid through a grid leak condenser 14, and the condenser is shunted by a leak resistor 15. The plate of tube 8 is connected by a lead 16 to one side of the feed-back coil 17, and the opposite terminal of the feed-back coil 17 is connected by a lead 18 to the point 19 on the divider R_1 . The screen grid of tube 8 may be connected to the desired positive point on the divider R_1 .

15 The feed back coil 17 is inductively coupled, as at M_5 , to the coil 12 to provide a feed-back circuit capable of producing local oscillations. Any desired type of radio frequency transmission network may be employed to impress the local oscillation energy from the local oscillator upon the first detector for the production of the intermediate frequency energy. In order to preserve simplicity of description, such a network has been shown in the drawing as comprising a pair of coils connected to form a link circuit, one of the 20 coils 20 being coupled, as at M_6 , to the feed-back coil 17, and the other coil 21 being coupled, as at M_7 , to the coil in the input circuit of the first detector.

25 The resonant grid circuits of the radio frequency amplifier, first detector and local oscillator stages have their variable tuning condensers arranged for mechanical uni-control. For economical factory production these three variable condensers are made similar, and the rotor elements are mounted on a common operating shaft, conventionally designated by dotted lines 22 in the drawing. In order to constantly maintain the resonant grid circuit of the local oscillator differing from the resonant grid circuits of the 30 radio frequency amplifier and first detector by the desired operating intermediate frequency, the usual shunt and series trimmer condensers may be employed in the circuit 12, 13.

35 It is not believed necessary to complicate the present description and drawing by showing these trimmer condensers since this has been clearly shown by W. L. Carlson in U. S. Patent 1,740,331 of December 17, 1929. With these trimmer condensers the local oscillator variable condenser 13 may be adjusted to tune the local oscillator through a frequency range differing from the broadcast signal range at all times by the operating intermediate frequency. The manual volume control employed in the receiver described 40 heretofore comprises the variable resistor R in series with the fixed resistor R_2 . The resistor R varies the bias on the radio frequency and intermediate frequency amplifier tubes 1 and 5, preferably putting more bias on the tube 1 than on the 45 tube 5. The resistors r_1 and r_2 provide the

5 normal bias when the resistor R is adjusted to its maximum setting. As the magnitude of the resistor R is decreased to reduce the amplification of the radio frequency and intermediate frequency stages, the potential difference between the anode and cathode of the local oscillator tube 8 decreases, thus decreasing the local oscillator strength, and hence still further reducing the over-all gain of the receiver.

10 The advantages of having the volume control affect the local oscillator strength in addition to the amplifier biases may be summed up as follows:

15 (1) The reception of local broadcast signals, these signals being from powerful stations in the vicinity of the receiver, constitutes most of the activity of the average broadcast receiver. Since this must be accomplished with reduced oscillator strength, because when receiving strong local signals the resistor R would be adjusted to 20 decrease the over-all gain of the receiver, radiation interference is greatly lessened.

25 (2) When receiving local stations, which means reduced over-all gain of the receiver, less heterodyne voltage is applied to the frequency changer tube, the first detector thereby giving less distortion or higher order effects.

30 (3) There is secured a greater control of the over-all gain of the receiver with the same variation of the usual volume control resistor R .

35 Other operating advantages will be obvious to those skilled in the art. It should be pointed out that the invention is not limited to the use of a single radio frequency amplifier tube and a single intermediate frequency amplifier tube, but it should be obvious that a plurality of radio frequency or intermediate frequency tubes may be employed. In this case, it is only necessary to multiply the present connections from these additional radio frequency and intermediate frequency 40 amplifier tubes to the power supply resistor R_2 .

45 The local oscillator circuit shown is substantially stable with regard to frequency shift. That is to say, the local oscillator frequency will not shift appreciably with changing operating voltages. The grid leak condenser 14 should be small, and the leak resistor 15 of a relatively high resistance value. The cathode resistor 11 is preferably not by-passed. With this type of oscillator circuit any frequency shift which may 50 occur due to plate impedance variation is substantially neutralized by the frequency shift due to the grid circuit impedance variation. In this way, the potential difference between the plate and cathode of the oscillator tube 8 may 55 be varied without causing frequency drift of the local oscillator circuit.

60 While I have indicated and described one system for carrying my invention into effect, it will be apparent to one skilled in the art that my invention is by no means limited to the particular organization shown and described, but that many modifications may be made without departing from the scope of my invention as set forth in the 65 appended claims.

What I claim is:

65 1. In a superheterodyne receiver, a first detector, a second detector, an intermediate frequency amplifier coupling the first and second detectors, a radio frequency amplifier coupled to the input of the first detector, a local oscillator connected to the first detector, and a manual volume control device for said receiver comprising a common means for simultaneously varying the gain of said radio frequency and inter- 70

mediate frequency amplifiers and the intensity of the local oscillations impressed on said first detector, said common means including an adjustable potential source connected to the cathode circuits of said oscillator and amplifiers.

2. In a superheterodyne receiver of the type including a radio frequency amplifier, a first detector, an intermediate frequency amplifier and a local oscillator circuit, a common potential source for the various circuits of said amplifiers and said local oscillator, and a common resistor means connected to the said potential source and said amplifier and local oscillator circuits for simultaneously increasing the gain of said amplifiers and the intensity of local oscillations impressed on the first detector.

3. In a superheterodyne receiver of the type including a tunable radio frequency amplifier circuit, a first detector circuit and local oscillator means for impressing locally produced oscillations on said first detector circuit means coupling the output circuit of said amplifier to the input circuit of said detector, a manual volume control means for said receiver comprising a unitary device for simultaneously decreasing the gain of said amplifier and the strength of said locally produced oscillations, said device consisting of an adjustable voltage source connected to the cathode circuits of the amplifier and oscillator.

4. In a heterodyne receiver of the type having a frequency changer circuit and a local oscillator coupled thereto for impressing local oscillations thereon, said oscillator comprising an electron discharge tube having grid and plate circuits, a manual volume control device for regulating the amplitude of the said oscillations consisting of a source of direct current energy, a resistor connected between said source and the plate of said oscillator, variable resistor means connected to the said source for varying the potential difference between the cathode and plate of the oscillator and a resistor common to the grid and plate circuits of said oscillator and having one end connected to the low potential end of said variable resistor and its other end to said oscillator cathode.

5. In a heterodyne receiver of the type including a frequency changer circuit and a local oscillator coupled to the circuit for impressing local oscillations thereon, a device for regulating the amplitude of the said oscillations consisting of a source of direct current energy con-

nected in the space current path of said oscillator, means connected to the said source for varying the potential difference between the cathode and anode of the oscillator, a radio frequency amplifier having a tuned grid circuit, a cathode, and a plate circuit coupled to the changer circuit, a connection to ground from one end of said grid circuit, a resistor common to said plate and grid circuits and a connection between one end of said resistor and said varying means whereby regulation thereof simultaneously changes the bias of said amplifier grid.

6. In a superheterodyne receiver of a type including at least a radio frequency amplifier, intermediate frequency amplifier and local oscillator, a source of direct current energizing potential for said amplifiers and oscillator, and a single variable resistor connected between the said source and space current paths of said amplifiers and oscillator for adjusting the volume of the receiver.

7. In a superheterodyne receiver, a super-audible frequency amplifier and a local oscillator having plate and grid circuits, a source of direct current potential connected to the electrode circuits of the amplifier and oscillator, and a manual volume control device for the receiver comprising means to simultaneously adjust the cathode potential of the amplifier and the cathode potential of the oscillator a resistor common to the grid and plate circuits of said oscillator and a lead connecting one end of said resistor to one terminal of said volume control device.

8. In combination in a heterodyne receiver, a source of direct current voltage, a first resistor connected across the terminals of said voltage source, a second resistor connected across said voltage source and having at least a portion which is variable, a local oscillator having a cathode and plate, a connection between the plate and an intermediate point of said first named resistor, a radio frequency amplifier tube having a cathode, control grid and plate, a first detector having a tunable input circuit coupled to the plate circuits of said amplifier and oscillator, and connections between the cathodes of said oscillator and said amplifier tube and intermediate points of said second named resistor whereby adjustment of the variable portion thereof simultaneously increases the gain of said amplifier tube and the output voltage of said local oscillator.

WALTER VAN B. ROBERTS.
